UNITED STATES PATENT OFFICE

2,432,311

PROTECTOR HOOD

Anna Ford Hall, Ansonia, Conn.

Application February 2, 1946, Serial No. 645,062

3 Claims. (Cl. 128—146)

1

This invention relates to nasal and lung protectors, and aims to provide an efficient and practical protective means for use by workers in such trades or industries where fine particles of dust or liquid globules are present in the ambient atmosphere, whereby the worker can breathe freely without inhaling the dust or liquid particles. It is well known that serious trouble can result from such inhalation, and it is believed that the utilization of the protector herein presented will effectively prevent such particles from being breathed in by the worker.

The above broad as well as additional and more detailed objects will become apparent in the following description, wherein characters of reference refer to like-numbered parts in the accompanying drawings. It is to be noted that the drawings are intended for the purpose of illustration only, and that it is neither desired nor intended to limit the invention necessarily to the specific details of construction shown excepting insofar as they may be deemed essential to the invention.

Referring briefly to the drawings,

Fig. 1 is a front elevational view of the protective hood.

Fig. 2 is a rear elevational view of the same.

Fig. 3 is a cross-sectional view taken on the line 3—3 of Fig. 1.

Fig. 4 is a cross-sectional view taken on the line 4—4 of Fig. 1.

Fig. 5 is a cross-sectional view taken on the line 5—5 of Fig. 1.

Fig. 6 is a fragmentary side elevational view of the protector.

Referring in detail to the drawings, the numeral 10 indicates the shoulder portion and the numeral 11 the head portion of a cape-like hood adapted to cover the head, neck and shoulders of the wearer. The head portion 11 comprises a substantially cylindrical member having the front and rear walls 12 and 13, respectively, joined by the enclosing peripheral side wall 14 having an opening 15 at the bottom for the neck of the wearer. The shoulder portion 10, which is shaped as seen in Figs. 1 and 2 to register over the shoulders and part of the neck of the wearer, comprises at the rear the cover or back 16 which is a unitary continuation of the head portion 13. At the front of the shoulder portion 10, the cover member 17 depends from the lower portion of the head portion 10. Shoulder strips 18 join the complementary upper edges of the shoulder cover members 16 and 17.

An opening 19 is formed in the member 12 to

2

provide a vent for the mouth, and around this opening a flange 20 is formed about which a cap 21 is slidably mounted, the outer end of the cap having the opening 22 therethrough surrounded by the flange 23. A perforated closure strip 24, backed by a filter pad of any desired construction or material 25, which registers against a filler flange 26 mounted within the flange 20, serves to permit air to enter through the opening 19, and the filter serves to trap any dust or liquid particles which may abound in the air. The cap 21 is readily removable from the flange 26, being retained thereon frictionally, for replacement of the filter and cleaning the perforated closure 24.

Spaced eye openings 27 are likewise formed in the face member 12, and a circular flange 28 surrounds the same, about which registers frictionally the cap having its end 29 open and provided with the flange 31. An inner filler flange 32 is mounted within the flange 28, and a plain glass disk 33 is thus removably clamped between the flanges 31 and 32, so that the glass may be removed for cleaning. The eye openings are thus sealed.

A nose opening 34 is also formed in the face member 12, surrounded by the flange 35, in which a filler flange 36 is mounted. A cap 37 frictionally and removably surrounds the flange 35, and its end is open at 38 and surrounded by the flange 39. Behind the flange 39 a perforated disc 40, backed by a filter pad 41, registers, and both the disc and the pad are thus removably clamped between the flanges 39 and 36, so that both may be removed readily for cleaning or replacement. The construction of the ear members 42 is substantially similar to that shown for the nose member, and the ear members have therefore not been illustrated in detail.

The bottom of the shoulder member 10 is, of course, although not shown, open, so that the entire hood may be slipped on the wearer over the shoulders, with the head registering in the portion 10. Of course no dimensions are shown or indicated, but it is to be understood that the various parts of the device are to be so proportioned and dimensioned as to permit its functioning as and for the purposes set forth.

When the hood is used in the manner stated, the wearer may breathe freely through the nose member or, also, the mouth member, and he may hear through the ear members and see through the eye members. Meanwhile the hood fits the entire shoulder, neck and head of the wearer, covering those parts completely so that no dust or liquid particles may be breathed in while he

is present in a room or place where the air is thus contaminated. In this way the worker is protected from the consequences, which are frequently serious, of inhaling such particles into his nasal or sinus passages and the lungs.

The entire device may be readily and inexpensively made of any suitable material, such as, for instance, a cellulose acetate plastic material, or any other plastic material which may be adaptable to the purpose. The material would be light in weight yet sufficiently sturdy. To facilitate putting the hood on or taking it off, a slide fastener closure 43 is provided at the vertical median line of the back member 13-16, extending from a point near the top of the head member to and through the lower edge of the back shoulder member 16. The wearer himself may, therefore, readily apply or remove the hood on himself. When the hood is thus worn, and the slide fastener closed, the lower peripheral edge of the shoulder member 10 closes snugly about the shoulders of the wearer and thereby prevents leakage of dust-laden air into the hood.

The feature of making the mouth, nose, eye and ear closures removable for cleaning or replacement of the filters, is important in that such cleaning or replacement may be made quickly and readily with a minimum loss of time to the worker.

Obviously, modifications in form and structure may be made without departing from the spirit and scope of the invention.

I claim:

1. A hood of the class described comprising a unitary head member and shoulder member, said

head member comprising a substantially cylindrical hollow member having front and rear faces having openings through the face thereof for eyes, nose, and mouth, and openings through the front cylindrical wall thereof for ears, said nose, mouth, and ear openings having perforated closures removably mounted therein and having removable filters mounted therein behind said closures, said hood having slide fastener means for tightening the lower edge of the same about the shoulders of the wearer.

2. The hood set forth in claim 1, said slide fastener means being positioned along the vertical median line of the hood at the back thereof and extending from a point near the top of said head member down to and through the lower peripheral edge of said shoulder member.

3. The hood set forth in claim 1, said eye members having glass disks removably mounted thereon.

20 in.

ANNA FORD HALL.
